UNITED STATES PATENT OFFICE.

FRANCIS H. RICHARDS, OF HARTFORD, CONNECTICUT, ASSIGNOR, BY MESNE ASSIGNMENTS, TO AMERICAN TYPOGRAPHIC CORPORATION, A CORPORATION OF ARIZONA TERRITORY.

MACHINE FOR MAKING TYPE-BARS.

947,006.

Specification of Letters Patent.

Patented Jan. 18, 1910.

Original application filed January 14, 1899, Serial No. 702,124. Divided and this application filed July 13, 1901, Serial No. 68,137. Renewed October 9, 1909. Serial No. 521,951.

To all whom it may concern:

Be it known that I, FRANCIS H. RICHARDS, a citizen of the United States, residing at Hartford, in the county of Hartford and

5 State of Connecticut, have invented certain new and useful Improvements in Machines for Making Type-Bars, of which the following is a specification.

This invention relates to a machine for 10 making composite typebars, each bar comprising a body-piece or type-support constructed to receive a series of types by an interlocking engagement between the support and the series of types distributed 15 along the edge of the support to form words and word-spaces, as may be desired.

The present application forms a division 20 of an application for Letters Patent filed by me on January 14, 1899, Serial No. 702,124, for the manufacture of typebars, the subject matter of this present application was included in an application for Letters Patent on a machine for forming typebars divided out of said application, Serial No. 702,124

25 and filed by me on May 3, 1900, Serial No. 15,299, and renewed September 19, 1909, Serial No. 453,821. In this latter application there is shown, described and claimed an organization of mechanism for making a 30 composite typebar in which organization there is included a mold-box designed to coöperate with successive portions of the edge of a typebar body-piece or type-support and in conjunction with selectively- 35 located dies to form a series of types disposed along the edge of such body-piece. It is proposed, as set forth in that application, to justify the matter forming the line of types by some suitable mechanism.

40 The mold feature is claimed in such other application; and certain type head severing, type head shifting and justifying mechanism, illustrated in practice herein, are also claimed in conjunction with said mold in

45 said other application. Claims to the art of forming typebars in a closed mold from solid metal and interlocking these with a body piece are included in the parent application, Serial No. 702,124.

50 The present application is directed more especially to those fundamental features of organization which are essential for the pro-

duction of a line of composed types along a proper typebar body-piece or type-support to constitute a typebar of a composite nature.

In the machine herein set forth, as in that set forth in my hereinbefore-mentioned application, the type-support will usually be fed along intermittently, or step by step, 60 relatively to a type-forming mechanism, by which latter means type-material (preferably supplied to the machine in the form of a wire of proper cross-section) will be shaped into regular heads, and at the same 65 time each head thus formed may be interlocked with the type-carrying edge of the type-support or carrier portion of the completed typebar. In some cases this interlocking will be effected by placing the type- 70 head in engagement with the outside of a T-shaped or other suitable form of type-guide rib on the edge of the typebar body-piece, while in other cases each head will be forced into a suitable retaining groove 75 formed in the edge of such piece.

My improved typebar-machine is distinguished from all others of which I have knowledge by the fact that an essential feature thereof is the provision of mechanism 80 for compressing the individual type-blank onto and into engagement with a suitable type-support to form a type-head engaged or interlocked with such support. This act of compressing the material or blank results 85 not merely in the compression of the material into engagement with the support, but also in the formation of the type-head itself, and hence the molding of the type and the interlocking thereof with the support may 90 in practice be simultaneously effected and result from one operation.

In the preferred construction, and for the purpose of readily justifying the types, the type-support or typebar body onto which the 95 type-heads are molded will be so constructed that the finished types will be capable of being shifted or slid along such body, and hence I make use of a typebar body or type-support in which there is a type-guide of uniform character throughout its length, this guide being on one edge of the typebar body, and consisting of a rib or tongue projecting therefrom, or a groove or channel cut there-

in, and with which the material of the type-blank may be engaged by the compression thereof.

The machine embodied in the present invention will comprise as an important feature thereof type-forming mechanism co-operative with the type-support or typebar body-piece to compress and hence form on the latter and in engagement therewith a type or row of types which will be shaped in place. In the preferred construction and mode of operation the type-support or typebar-body will form a wall corresponding to the bottom wall of a mold against which the type-blank is forced when operated upon by the die to form the blank into a type-head and interlock the same with the edge of the support or body-piece.

In a complete mechanism for producing a typebar of the present character it is desirable to feed the typebar body-piece with which the type-heads are engaged different distances, step by step, according to the size of the head to be formed, and a construction operative in this manner is shown herein. Moreover, while the type-material may be supplied to the type-making point of the machine in any proper manner, I deem it desirable to feed a type-blank rod from which rod type-blanks will be severed or sheared, these type-blanks being of such lengths as may be necessary for the formation of the respective type-heads; hence, this rod may also be fed different distances and a variable feed device is provided herein for this purpose. After the formation of the type-heads to form a line of types, any excess material may be sheared therefrom and the heads trimmed by some suitable mechanism in a manner well understood by those familiar with the art.

In the drawings accompanying the present specification, Figure 1 is a sectional end elevation, partly an outline, of a portion of an apparatus for making typebars, illustrating a simple form of mechanism for carrying my invention into effect for producing composite typebars. Fig. 2 is a side elevation thereof, with parts broken away and with the stock-feeding device removed. Fig. 3 is a perspective view, on a somewhat enlarged scale, illustrating a partially completed typebar produced by the present machine. Fig. 4 is a transverse section of the typebar-body with the type-blank in position thereon before compression. Fig. 5 is a similar view illustrating said type-blank as having been compressed by a type-die to form a type-head. Fig. 6 is a perspective view illustrating the typebar body-piece and its feed-rod; and Fig. 7 is a plan view of various parts located at and adjacent to the type-making point of the machine.

Similar characters designate like parts in the different figures of the drawings.

The several operative parts of the mechanism will be mounted upon framework, designated in a general way by A, and comprising a base-plate 22. Upon this framework there will be mounted some suitable form of type-making mechanism, the mechanism, as herein shown, embodying orbitally-movable rotatable type-dies which are represented as carried by a rotating turret T substantially in the manner shown and described in my prior patent No. 403,216, granted May 14, 1889, to which reference may be had for a more detailed description of the several parts. This turret T is here mounted for rotation in an end frame 2 and an upright 2' both rising from the main framework A, and in this case also, the turret carries four shafts, such as 3, on which are carried die-wheels w provided with proper type-dies, such as those designated by d. Each of the shafts 3 will also carry a suitable starting-arms, such as s.

For the purpose of starting the starting-arms and hence the shafts of the die-wheels and the dies rotating, I may make use of the usual starting-latches, represented herein in a conventional way, and designated by l, (the latches shown being spring-pressed ones) which latches when tripped will start the rotation of the shafts and will be reset or returned to their normal positions by the starting-arms s, substantially in the manner described in said patent. As many latches may be used as there are type-dies on the die-wheels, but only four are illustrated herein. It will be obvious, of course, that the main shaft 4 carrying the several members of the turret T should be rotated in order to effect the rotation of the die-wheels when any starting-arm comes into contact with a latch that may be set, and for the purpose of rotating the turret I have shown a crank or handle 14 which, it will be understood, will be given at least one turn each time a latch is set.

The end frame 2 is shown as provided with a suitable internal gear, designated by 7, with which the teeth of the gear-wheel segments 8 attached to the die-wheel shafts will mesh when said shafts are started rotating.

The gear-segments 8 on the shafts 3 will be rotated selectively one at a time as the latches l are selectively operated, and when any gear-segment, its shaft and the die-wheel thereon have been started rotating, the rotation of each wheel, etc., will be stopped in some suitable manner at the proper point, as, for example, by a spring-pressed detent 9 coming in contact with a flattened portion of the hub of the gear-segment.

In my previously-mentioned application from which the present one is divided, a mold is shown co-operative with each die in

succession as it is brought to the type-making point and rolled over the type-blank located in such mold to form therefrom a type-head. The employment of such a mold 5 is convenient in that it offers one means for assisting in the ready production of a regularly formed type-head, and also as set forth in that application, for shearing surplus material in excess of that needed for the formation of the type-head. Satisfactory types 10 may be formed, however, without the use of such mold and any surplus material which it is desirable to remove may be trimmed off by any of the well-known means commonly 15 used in the art for trimming linotypes or typebars. The mold may therefore be omitted as a coöperative type-making member for the production of the successive type-heads and each type result solely from the 20 type-forming action of the corresponding die upon the blank.

The end of the plunger 13 farthest from the die is connected to a pin or stud 25' eccentrically mounted on a short spindle 25 25 suitably journaled in the base-plate 22 and having secured thereto an operating handle or lever, such as 26, from which projects a pin or detent 26'. The body of the lever 26 is resilient in order to permit a slight rising 30 and lowering of the detent-pin 26' which, in this case, will have an extreme range of movement between two stops 27' depending from a projection or plate on the framework. In the under side of this plate, there 35 may be a series of recesses, such as 27'', into any one of which the end of the pin 26' may be slipped for the purpose of locking the pin and the lever temporarily in place, the distance between the stops 27' corresponding 40 to the extreme range of movement of the slide 13, while the distance between consecutive locking recesses 27'' represents unit spaces as does also the intervals between the stop-pin 27' and the locking recess adjacent thereto.

In the present illustration of a simple organization, the group of dies carried by the four shafts 3 are of four different widths, and the right-hand stop-pin 27' and the 50 locking recesses 27'' are so located and spaced as to permit the adjustment of the slide 13 to control the production of finished types or type-heads of four different widths. Hence, if the lever is shifted from its normal position—in which it is in contact with the right-hand stop-pin 27' until the pin 26' reaches the first locking recess 27''—a type-head one unit wide may be formed, and if the lever is shifted to the second, third, or 55 fourth recess 27'', type-heads two, three, or four units wide, as the case may be, will be formed. The extreme movement of the lever 26 from one stop-pin to the other is intended to be independent in point of time of the 60 shorter movements just described and such

extreme movement may serve the purpose, in addition to another to be adverted to presently, of shifting the finished type along the type-guide of the body-piece *b* and locating it in its proper or final position on 70 the typebar body unless, of course, a repositioning thereof should become necessary for justification, although the shifting of a formed type-head out from under the dies to permit a second head to be made, may and 75 will in practice generally be accomplished by imparting a movement to the body-piece *b*, as will presently appear.

Not only does the typebar body have a type-guide but so does the actuating device 80 or feed-slide by means of which such typebar body is shifted or fed, to permit the terminal type or types of the line to be made upon the feed-slide and afterward shifted onto the typebar body, although such type 85 or types may generally be made directly on such body-piece. Still for the purpose of allowing the plunger 13 to move freely to and fro such feed-slide will ordinarily be provided with a type-guide, such as *g'*, similar to and in alinement with the guide *g* on the typebar body-piece. This feed-slide may also be of any suitable construction and may be substantially of the form shown herein. Here it is a vertically-disposed slide 30 in 90 alinement with and substantially of the same cross-section as the body-piece *b*. The feed-slide 30 is connected to and is operated in unison with a feed-screw 32, the body-piece occupying a position between the feed-slide and a similarly disposed keeper 30' at the opposite end of the body-piece. This feed-screw may be operated in any suitable manner, in this case a bevel-pinion 33 being 95 shown which feeds said feed-screw lengthwise but is so mounted in some suitable manner as not to travel longitudinally therewith. The pinion 33 may in turn be operated by another pinion 34 carried by a spindle 35 suitably mounted and having 100 thereon an operating wheel or dial 35' having an index *i* coacting with a pointer 36 on a fixed portion of the framework. By turning this index-wheel the feed-slide 30 and hence the typebar body *b* may be fed forward to shift the formed type out from under the dies and bring the next portion of the typebar body-piece under the dies, depending upon the position of the next type 105 to be formed.

In the construction shown, the slide 13 coacts with the feed-slide 30. For this reason I deem it desirable to support the slide 13 on the type-guide *g* of the feed-slide 30, and from the drawings it will be seen that 115 said slide 13 is guided on the projecting rib *g'*. If it is desired to form the last type of a complete series on the feed-slide 30 the described construction will permit this to be done in exactly the same manner as the 120 125 130

preceding type of such series have been formed on the body-piece *b*. After being finished, of course, the finished type will be shifted from the slide 30 by the slide 13 onto the typebar body-piece.

5 The material from which the type-heads are to be formed will be suitable for the purpose and be delivered at the type-making point under the die in proper manner, but I prefer to feed intermittently a type-blank rod, such as *r*, which may be fed in any suitable manner as by means of a pair of feed-rolls *f*, *f'*, the former of which has a graduated periphery or index *i*' composed of equidistant graduations with which a suitable pointer on the framework, such, for example, as the finger designated by 4 coöperates.

10 The feed-roll *f* may be turned by a handle 4' to feed the rod any desired distance which, it will be understood, will depend upon the width of the type-head to be formed, the graduations of the feed-roll *f* corresponding to those of the index *i* and also to those between the recesses 27''. When a proper 15 length of the rod has been fed forward a type-blank *r'* will be severed therefrom in some suitable manner. The slide 13, shown in the present organization, offers a convenient 20 means for coöperating with the edge 13' of the stock guide 13'' for shearing off consecutively the separate type-blanks, it having an edge 13* coöperative with the edge 13' of the stock guide 13'' for severing a blank upon the 25 forward movement of said slide, although it will be understood by those familiar with this and allied arts that the type-die itself may be so formed as to shear a blank from the rod immediately prior to its operation in 30 shaping the blank to the form of a type-head. 35 A die performing such two-fold function will be recognized by those skilled in the art as commonly utilized in the stamping and shaping of various articles from stock larger than the blank necessary to form the individual product. The amount of material so 40 cut off may vary according to the size of the type to be formed. The material in excess of that necessary to form a type-head will 45 be disposed of in a suitable way, as by trimming off the same, an operation commonly adopted in the finishing of linotypes and typebars. Some of the views show type-heads having a fin (see for example *x*) at the 50 side which will ordinarily result from the application of a die, necessitating a subsequent trimming operation.

55 The operation of an apparatus such as has been described hereinbefore for producing an improved typebar of the class specified is as follows: It being assumed that there is a finished type-head directly under the die the feed-screw 32 will ordinarily be operated to carry the typebar body-piece 60 endwise and shift the type-head out from

under the die and bring the proper portion of the type-support or body-piece in the plane of movement of the dies. Thereafter one of the latches *l* may be tripped, such latch corresponding, of course, to the type 70 to be formed. The handle 4' should then be operated to turn the feed-roll *f* a distance corresponding to the width of the type which the latch just operated represents and the rod *r* will thereupon be fed forward and 75 a portion of the rod will then project over the body-piece. The lever 26 is then shifted from its right-hand position until the detent-pin 26' comes opposite and slips into that recess 27'' which corresponds to the 80 width of the type to be formed, during which movement the lever 26 and the slide 13 cause the shearing off of a type-blank *r'* from the rod *r* and the transfer of such blank into the plane of movement of the 85 dies. The handle 14 may now be turned to start the turret rotating and when the proper starting-arm comes in contact with the actuated latch, such starting-arm and its shaft and die-wheel will begin to rotate and this 90 rotation will continue until the orbitally-movable rotating type-die corresponding to the latch selected is brought with a rolling action into contact with the type-material or blank and compresses the latter, thus simultaneously forming a type-head corresponding to such type-die and engaging or interlocking said head with the type-guide on the typebar body or type-support, or on the feed-slide, as the case may be. Of course, 95 each time the handle 14 is operated it should be given a complete turn, during the first part of which the starting-arm will commence rotating and afterward will reset the operated latch. This series of operations 100 may, of course, be repeated at will to produce a series of selected types of varying widths which may be properly spaced along the typebar body either by leaving a blank space between the separated groups of words, 105 or by forming quads between the word-groups in the same manner that the several type-heads *g* are formed. Manifestly, the spaces which may be left between the word-groups or other groups may be of varying 110 widths according to the manner in which the several parts are operated.

115 Having described my invention, I claim—

1. In a machine for making typebars, the combination with means for sustaining a type-support or body-piece, of a series of type-forming dies supported and adapted for being brought one at a time into a given working position to make types; means for operating a die and the type-support one toward the other for forming stock into a type-head engaged with the support; and means for feeding the support on the retraction of the die to carry the type away 120 from said working position of the die and 125 130

- place the support in position for receiving the next type-head.
2. In a machine for making typebars, the combination with means for sustaining a type-support or body-piece having a type-retaining guide, of a type-die, one of said members being operable toward and from the other for forming stock into a type-head engaged with said guide, and the members being adapted to have a relative movement whereby a second type may be formed and engaged with the guide.
3. In a machine for making typebars, the combination with means for sustaining a type-support or body-piece having a type-retaining guide, of a type-die movable in a curvilinear path toward and from said type-support for forming stock into a type-head engaged with said guide.
4. In a machine for making typebars, the combination with means for sustaining and feeding a type-support or body-piece having a type-retaining guide, of an orbitally-movable rotatable type-die coöperative with the support for forming type material into a type-head engaged with the type-guide.
5. In a machine for making typebars, the combination with means for sustaining a type-support or body-piece having on one edge thereof a type-guide and with feeding mechanism for said type-support, of a type-forming mechanism embodying type-dies coöperative selectively with the type-support for forming type material into type-heads engaged with the type-guide.
6. In a machine for making typebars, the combination with means for sustaining a type-support or body-piece, of type-forming and shifting mechanism operative for forming stock into a finished type-head on said support and then shifting the finished type-head along such support.
7. In a machine for making typebars, the combination with means for sustaining a type-support or body-piece having a type-guide on one edge thereof, of type-forming and shifting mechanism operative for first forming stock into a finished type-head engaged with the type-guide and then shifting the finished type-head along the guide.
8. In a machine for making typebars, the combination with means for sustaining a type-support or body-piece, of a series of type-forming dies supported and adapted for being brought one at a time into a given working position to make types; means for conveying stock into a position to be operated upon; means for severing a type-blank from such stock; means for operating a die and the type-support one toward the other for forming a type-blank into a type-head engaged with the support; and means for shifting such type-head from under the die and placing the support in a position for receiving the next type-head.
9. In a machine for making typebars, the combination with means for sustaining a type-support or body-piece, of a series of type-forming dies supported and adapted for being brought one at a time into a given working position to make types; means for conveying stock into a position to be operated upon; a slide for severing a type-blank from such stock; means for operating a die and the type-support one toward the other for forming a type-blank into a type-head engaged with the support; and means for shifting such type-head from under the die and placing the support in a position for receiving the next type-head.
10. In a machine for making typebars, the combination with means for sustaining a type-support or body-piece, of a series of type-forming dies supported and adapted for being brought one at a time into a given working position to make types; means for conveying stock into a position to be operated upon; a slide engaging with the type-carrying edge of such type-support for severing a type-blank from such stock; means for operating a die and the type-support one toward the other for forming a type-blank into a type-head engaged with the support; and means for shifting such type-head from under the die and placing the support in a position for receiving the next type-head.
11. In a machine for making typebars, the combination with means for sustaining a type-support or body-piece, of a series of type-forming dies supported and adapted for being brought one at a time into a given working position to make types; means for conveying stock into a position to be operated upon; a slide engaging with the type-carrying edge of the type-support and adapted to sever type-blanks of variable size from said stock; means for operating a die and the type-support one toward the other for forming a type-blank into a type-head engaged with the support; and means for conveying the support on the retraction of the die to carry the type-head away from said working position of the die and place the support in position for receiving the next type-head.
12. In a machine for making typebars, the combination with means for sustaining a type-support or body-piece, of a series of type-forming dies supported and adapted for being brought one at a time into a working position to make types; means for bringing stock into a position to be operated upon; a device for severing a section from such stock; means for operating the selected dies in succession to form types engaged with the support; and means for shifting a type from under the forming die to thereby permit a second type to be engaged with the support.
13. The combination with a type carrier

or support, of a feed slide for feeding such carrier or support; an adjustable slide reciprocatory in line with said support or carrier and said feed slide; and means for feeding stock across and into the path of the said adjustable slide whereby the forwardly moving slide may shear a blank from such stock.

14. The combination with a type carrier or support, of an adjustable slide, and means for feeding stock across and into the path of the slide whereby the forwardly moving slide may shear a blank from such stock.

15. The combination with a type carrier or support, of a feed slide for feeding such carrier or support; an adjustable slide reciprocatory in line with the upper edge of said support or carrier and the feed slide; and means for feeding stock across and into the path of the said adjustable slide whereby the forwardly moving slide may shear a blank from such stock, said adjustable slide engaging with the upper edges of said type carrier or support and said feed slide.

16. The combination with a type forming die, of an adjustable reciprocatory slide having an edge constituting one member of a shear, a coöperative shear member, and means for feeding stock variable distances to said coöperative shear member and across and into the path of reciprocation of the slide whereby the forwardly moving slide may shear a blank from the stock and advance the same to the working position of the die.

17. The combination with a type-carrier having a shear edge, of an adjustable slide

reciprocatory in line with said carrier and effective with said shear edge for severing the stock, and means for feeding the stock variable distances into the path of the slide whereby said slide may sever the stock at a predetermined point.

18. The combination with a series of dies, representing various unital values, of a reciprocatory slide and means for adjusting the same to correspond with the die unital values in the length of its path of movement, means for feeding stock across said path, and means coöperative with the slide for shearing the stock into type lengths.

19. The combination with a type carrier or support, of an adjustable slide, a coöperative shear face, and means for feeding stock across and into the path of the slide and over said shear face whereby the forwardly moving slide may shear a blank from such stock.

20. The combination with a type carrier or support, of a feed slide for feeding such carrier or support, an adjustable slide reciprocatory in line with said support or carrier and said feed slide, a rock shaft and means for rocking the same, an eccentric stud on said shaft, and a link connecting said stud and slide, and means for feeding stock across and into the path of the said adjustable slide whereby the forwardly moving slide may shear a blank from such stock.

FRANCIS H. RICHARDS.
